UNITED STATES PATENT OFFICE.

CLARENCE B. WILLIAMS, OF PENCE, AND IRA H. WILLIAMS, OF MAPLE CREEK,
SASKATCHEWAN, CANADA.

POWER-GENERATING MECHANISM.

1,177,465.

Specification of Letters Patent. Patented Mar. 28, 1916.

Application filed May 28, 1913. Serial No. 770,555.

To all whom it may concern:

Be it known that we, CLARENCE B. WILLIAMS and IRA H. WILLIAMS, respectively a citizen of the United States and a subject of the King of Great Britain, respectively residing at Pence and Maple Creek, in the Province of Saskatchewan, Dominion of Canada, have invented certain new and useful Improvements in Power-Generating Mechanism, of which the following is a specification.

This invention relates to a power generating mechanism adapted for general application or use, but specially intended to be comprised in the organization of a portable engine or motor of any type; and the main object of the same is to provide a plurality of elongated levers which are severally elevated by a prime motive mechanism and automatically depressed to actuate a driven shaft to increase the power generation of the said initially operating motive mechanism having a given pressure and concentrate said increased power on the driven shaft from which transmission may be effected by any suitable means to drive or operate other mechanism, and thereby minimize in the utilization of a motive medium with a relatively greater resultant power.

A further object of the invention is to provide power generating mechanism wherein a motive medium of a given pressure or known power producing result is materially increased in its effectiveness relatively to a driven shaft through power increasing devices interposed between the point of application of the motive medium and the driven shaft and having an automatic or gravitational movement to regularly actuate the driven shaft independently of actuation by the motive medium.

The invention consists in the construction and arrangement of the several parts which will be more fully hereinafter described and claimed in preferred form.

In the drawings: Figure 1 is a top plan view of a generating mechanism embodying the features of the invention. Fig. 2 is a longitudinal vertical section on the line 2—2, Fig. 1. Fig. 3 is a detail bottom plan view of one of the dogs for actuating the driven shaft and showing a relative rotating element in dotted lines and the pivotal support for the dog in section. Fig. 4 is a sectional elevation of a portion of the

mechanism for receiving the motive medium and operating the power increasing levers, the latter being shown in cross-section. Fig. 5 is a top plan view of a portion of the manifold, valves and operating means for the valves. Fig. 6 is an enlarged section taken in the plane of the line 6—6, Fig. 5. Figs. 7 and 8 are elevations, partially in section, of portions of the mechanism illustrating modifications. Fig. 9 is a detail plan view of a portion of the modification shown by Fig. 8.

The numeral 5 designates a bed or base which may be a part of a traction engine or other motor vehicle, or which may be stationary. This bed or base is of suitable dimensions to support the working parts hereinafter explained and comprises at one extremity a brace frame 6. A reservoir, tank or cylinder 7 is mounted on the bed or base and constitutes the receptive and distributing means for the motive medium which may be either steam under pressure or compressed air and has an inlet pipe 8 at the top or at any other suitable point, and a lower outlet pipe 9 provided with a valve 10, the outlet pipe 10 communicating with a manifold 11.

The tank, reservoir or cylinder 7 will be supplied with the motive medium from any suitable source, and while the motive medium may be steam or compressed air it will be understood that the invention is not in the least dependent upon the prime actuating means or the motive medium, and the tank, reservoir or cylinder shown is illustrated simply to demonstrate one practical means of supplying the apparatus with a prime motive medium. The bed or base 5 also supports in suitable bearings a driven shaft 12 which is the power shaft, and as shown by Figs. 1, 2 and 3, said shaft is provided with a plurality of ratchet wheels 13 spaced at intervals thereon and suitably secured or keyed to the shaft.

The shaft 12 may be properly termed the concentrating means for the power generated, and therefrom transmission of power to any suitable source or for driving any suitable mechanism may be taken through the medium of a gear or other preferred device 14 which is provided with a suitable clutch mechanism 15 for throwing in or cutting out the said gear or other device 14 relatively to the shaft 12. In the lower part 110

of the frame 6 a plurality of toothed segments or rockers 16 are pivotally mounted and have their upper enlarged extremities provided with teeth 17, and to each of the said toothed segments or rockers 16 a dog 18 is pivotally attached at its rear end and is of yoked or looped form to partially embrace the lower portion of the adjacent ratchet wheel 13, the dog having a biting edge 19 to engage the teeth of its ratchet wheel. All of the toothed segments or rockers 16 are provided with these dogs extending under the ratchet wheels 13 on the shaft 12, and the dogs are severally held up 10 in engaging position relatively to their ratchet wheels by bowed springs 20. On the opposite ends of the shaft 12 sprocket wheels 21 are mounted and have chain belts 22 trained thereover and extending downwardly and also trained over sprocket wheels 23 on the end of a cam shaft 24 mounted in suitable bearings in the bed or frame 5 adjacent to but slightly in advance of the manifold 11. The shaft 24 is provided with a plurality of wiper fingers or cams 25 which are spirally disposed on the shaft 24 so as to have a proper timed operation relatively to a plurality of valves 26 disposed in the top portion of the manifold 30 11, as clearly shown by Figs. 4, 5 and 6. The top of the manifold is formed with a plurality of cavities or valve seats 27 in which the valves 26 are mounted to have reciprocating or sliding movement. The valves 26 are flat and each has a port or opening 28 therethrough which is adapted to coincide or register with a corresponding port 29 in the top of the manifold 11, there being as many ports 29 as there are valves 40 26. Each valve 26 has a forwardly projecting stem 30 terminating in a yoked head 31 carrying a roller 32 for engagement with the adjacent wiper finger or cam 25 in the manner particularly shown by Fig. 6. Surrounding the valve stems 30 and between the yoke heads 31 and the adjacent side of the manifold 11, are springs 33 which operate to retract or restore the valves to normal position when released by the wiper fingers or cams 25. Adjacent to the ports 29 are exhaust ports 34 having exhaust pipes 35 communicating therewith, the said exhaust ports being alternately closed and opened by the movement of the valves 26. Over the valves 26 a cap or top plate 36 is disposed and has the ports 29 and 34 continued therethrough, said cap or top plate acting to hold the valves 26 in place in their seats. Mounted on the cap or top plate 36 over each valve 26 is an upright cylinder 37 through the bottom of which the ports 29 and 34 are also continued, and within each cylinder a piston 38 is mounted having a piston stem or rod 39 projecting upwardly through the top of the cylinder. It will be

understood that suitable packings will be introduced at all points where it is desired to form tight joints and avoid leakage of the motive medium. All of the cylinders 37 are of the same vertical extent, and the pistons 38 and stems or rods 39 thereof all have the same vertical stroke. The upper ends of the piston stems or rods are provided with open heads 40 which are practically in the form of closed yokes, and each head or yoke has an antifrictional roller 41 mounted in the lower portion thereof for a purpose which will be presently explained.

Rising from the bed or base 5 adjacent to the manifold 11 are guide frames 42, there being two of these frames disposed on opposite sides of the longitudinal center of the mechanism and having vertical slots or guide ways 43 in which elongated levers 44 are loosely disposed for unretarded vertical reciprocation, the ends of the levers projecting through the open heads or closed yokes 40 at the upper ends of the piston stems or rods 39 and engaging the antifrictional rollers 41. These levers 44 may be of any suitable length and extend forwardly to the frame 6 and are formed with elbows or bends 45 which continue into pivoted toothed segments or upper rockers 46 having their lower enlarged extremities provided with teeth 47 meshing with the teeth 17 of the segments or rockers 16. The segments or rockers 16 and 46 are held in continual mesh, and the object of the same is to provide a positive action under certain operating conditions that may be found necessary relatively to the dogs 18 when the levers 44 are vertically reciprocated. As will be hereinafter explained, however, these toothed segments or rockers 16 and 46 may be eliminated and the construction correspondingly simplified. On each lever 44 a weight 48 of suitable dimensions and proportions is adjustably held through the medium of a set-screw 49, the weights 48 being of sufficient size and having such avoidupois as to rapidly and positively depress the rear extremities of the levers when the latter have been elevated to their full extent in accordance with the strokes of the piston stems or rods 39. By adjusting the weights 48 on the levers 44 the strokes of said levers may be modified at will so as to give a long or a shorter throw to the dogs 18 cooperating with the ratchet wheels 13. From the foregoing explanation the operation of the power generating mechanism will be readily understood. The manifold 11 is supplied with the motive medium through the pipe 9 by opening the valve 10, and as one of the slide valves 26 will at the time be open so as to establish communication between the manifold and the adjacent cylinder 37 through the port 29, the piston 38 and piston stem or rod 39 in the said

cylinder will be forced upwardly and elevate the corresponding lever 44, thereby actuating the shaft 12 through the dog 18 set in motion, and the motion of this shaft 5 will be transmitted to the chain belts 22 back to the shaft 24 and thus regularly start all of the wiper fingers or cams 25 to regularly and alternately open the several valves 26 so that all the levers 44 may be 10 elevated in turn, and as soon as the levers reach their highest elevation in accordance with the projection of the piston stems or rods 39 above the cylinders, the weights 48 will immediately come into play and cause 15 the said levers 44 to automatically depress or gravitate and actuate the several dogs 18 and thereby regularly and rapidly rotate the shaft 12 with increased power relatively to the pressure of the motive medium. When 20 the pistons 38 have reached their highest stroke, the valves of each piston will be relieved of engagement with the wiper fingers or cams 25 and the springs 33 then come into play and immediately close the valves 25 or shut off the ports 28 relatively to the 25 ports 29 and open the exhaust ports so that the motive medium in the cylinders may be rapidly forced out through the pipes 35 just at the time that the levers start to 30 descend. It will be seen that the valves 26 close the exhaust ports when said valves are projected rearwardly by the wiper fingers or cams 25, and when the valves are 35 released and move forwardly the rear extremities of said valves clear the exhaust ports. The dogs 18 draw rearwardly on the ratchet wheels 13 and rotate said ratchet wheels when the levers 44 descend. When 40 the levers 44 are elevated by means just explained, the dogs 18 move in an opposite direction over the lower portions of the ratchet wheels to obtain a proper grip, all as clearly indicated by Fig. 2 in full and dotted lines.

45 In the form of lever shown by Fig. 7, all of the mechanism hereinbefore explained is used, but the toothed segments or rockers 16 and 46 are dispensed with or eliminated, but the levers are formed with extensions 50 and to the lower ends of these extensions the dogs 18 are pivotally connected and have springs 51 attached thereto and to the extensions, as clearly shown by Fig. 7. In all other respects the structure shown by Fig. 7 is similar to that heretofore described, and the piston stems or rods 39 similarly operate with the main portion of the levers 44. In the modification shown by Fig. 8 the lever 44 is slightly 55 modified in shape and has a downward and forward bend as at 52 and 53, the forward extremity 53 being continued into a yoke 54 in which a grooved wheel 55 is disposed, the shaft 12 extending through the opposite 60 sides of the yoke 54 and the grooved wheel

55. In the free extremities of the side members of the yoke 54 a smaller grooved wheel 56 is mounted and spaced a distance from the wheel 55. Coöperating with these two wheels is a wedge 57 having a convex contour corresponding to the grooves of the wheels 55 and 56, the said wedge being held down in biting relation relatively to the grooved wheels 55 and 56 by a spring 58 connected to the lower end of each wedge 75 and also to a portion of the bed or base below. The form of lever and operating mechanism shown by Fig. 8 is also actuated by the piston organization hereinbefore explained, and when the levers in this instance 80 are raised by the pistons the several grooved wheels 56 slip on their wedges 57 and on the return or depressing movement of the levers a bite is set up by the wedge between the wheels 55 and 56 and the wheels 55 are 85 thereby rotated and as a consequence revolve the shaft 12.

The several forms of the levers hereinbefore explained impart to the shaft 12 a regular rotation and the rapidity of rotation will of course depend upon the frequency or rapidity of action of the pistons or the supply of the prime motive means to the cylinders 37.

It will be understood that changes in the proportions, dimensions and minor details may be resorted to without departing from the spirit of the invention.

What is claimed is:

1. In a power generating mechanism of the class specified, the combination of a shaft upon which the power is concentrated, a plurality of devices fixed to the shaft for rotating the latter, supporting means at a distance from the shaft, a plurality of levers having the greater portions thereof free to swing vertically from a normal approximately horizontal position and fulcrumed on the said supporting means at a distance from the shaft, the levers being provided with extremities projecting beyond their fulcrums and having coöperating means engaging the devices on the shaft to alternately and uniformly set up a rotation of the said shaft, motive means including reciprocating devices loosely and longitudinally slidable on the extremities of the portions of the said levers free to swing to move the levers individually and vertically in alternation, and means also engaging the extremities of the portions of the levers free to swing adjacent to the points of engagement of the reciprocating devices with said levers for causing the levers and the reciprocating devices to automatically move into their normal positions.

2. In a power generating mechanism of the class specified, the combination of a shaft on which the power is concentrated, a plurality of devices fixed to the shaft for rotat-

- ing the latter, supporting means at a distance from the shaft, a plurality of levers fulcrumed on the supporting means and having elongated free portions normally disposed approximately in a horizontal plane or parallel to each other, the levers also having extremities projecting beyond the fulcrums thereof and provided with toothed segments, other toothed segments fulcrumed 10 on the supporting means and continually in engagement with those of the levers, resiliently supported devices coöperating with the toothed segments and held in continual engagement with the plurality of devices 15 fixed to the shaft to alternately and uniformly set up a rotation of the shaft, prime motive means including vertical reciprocating devices loosely slidable on the free portions of the levers for positively moving the levers vertically in alternation to actuate the toothed segments and the devices on the shaft, and means also on the free swinging portions of the levers for automatically moving the latter and the reciprocating devices 20 25 into normal position.
3. In a power generating mechanism of the class specified, the combination of a shaft arranged to have power concentrated thereon and provided with devices fixed 30 thereto for rotating the same, supporting means at a distance from the shaft, a plurality of levers with rear bent extremities fulcrumed on the supporting means, portions of the fulcrumed extremities of the 35 levers extending beyond the fulcrums thereof and having means coöperating therewith to engage and actuate the devices on the shaft and the latter in alternation to set up a uniform rotation of the shaft, the levers 40 having free elongated portions which are normally horizontally disposed in parallel relation, motive means including vertically reciprocating elements, one for the free portion of each lever, the reciprocating elements

having terminals slidably engaging the free 45 portions of the levers for raising the latter in alternation to actuate the shaft, and means coöperating with the free portions of the levers adjacent to the points of engagement therewith of the reciprocating devices 50 to effect a downward movement of the levers and the reciprocating devices to return the said parts to normal position.

4. In a power generating mechanism of the class specified, the combination of a shaft 55 arranged to have power concentrated thereon and provided with devices fixed thereto for rotating the same, a plurality of levers with rear bent fulcrumed extremities, portions of the levers projecting beyond the fulcrum means thereof and having devices coöperating therewith to engage and actuate the devices on the shaft to regularly rotate the latter through an alternate operation of the said levers, the levers having free elongated portions which are normally horizontally disposed in parallel relation, motive 60 means including vertically reciprocating elements, one for the free portion of each lever, the reciprocating elements having terminals 65 slidably engaging the free portions of the levers for raising the latter in alternation to actuate the shaft, and means coöperating with the free portions of the levers adjacent to the points of engagement therewith 70 of the reciprocating devices to effect a downward movement of the levers and the reciprocating devices to return the said latter parts to normal position.

In testimony whereof we have hereunto 80 set our hands in presence of two subscribing witnesses.

CLARENCE B. WILLIAMS.
IRA H. WILLIAMS.
